SLICING MACHINE

Adrianus van Duyn, Rotterdam, Netherlands, assignor to U. S. Slicing Machine Company, La Porte, Ind., a corporation of Indiana

Application February 28, 1928, Serial No. 257,750,
and in Great Britain April 21, 1927

34 Claims. (Cl. 146—102)

This invention relates to slicing machines of the kind in which the substance to be sliced is moved to and fro past a slicing knife, or, conversely, the knife is moved to and fro past the substance, the stroke of the movements being variable at will to suit the width of the substance. In such machines, it is usual to provide feed mechanism for automatically advancing the substance across the cutting plane of the knife, prior to each slicing stroke, by an amount equal to the thickness of the slice to be cut. It is desirable that the slices cut during a series of slicing strokes should be of the same thickness, and, to effect this, it has previously been proposed to provide slicing machines with devices which are subject to the disadvantage that they require to be adjusted in accordance with the length of the slicing stroke, this length being dependent upon the width of the substance to be sliced.

This invention has for its object to remove the above disadvantage and to this end comprises slicing machines in which the carrier for the substance to be sliced (or the carrier of the slicing knife) actuates, in its stroke, the feed mechanism of the machine in such manner that equal feed movements are transmitted to the substance (so as to obtain slices of the same thickness) in spite of any variation in the magnitude of the strokes of the carrier and without the necessity for adjusting any of the working parts.

The slicing machine preferably has a member arranged to move in unison with the substance-carrier, or the knife-carrier, throughout part of the slicing and return strokes, the arrangement being such that relative movement between the substance-carrier, or the knife-carrier, and said member results in actuation, to a predetermined extent, of the feed mechanism of the machine, irrespectively of the magnitude of the stroke.

When the invention is applied to a machine of the reciprocatory carriage type, the member may be adapted to slide in unison with said carriage along one of the carriage guides throughout part of the slicing and return strokes, the arrangement being such that relative movement between the carriage and said member results in actuation, to a predetermined extent, of the feed mechanism. When the invention is applied to a machine of the reciprocating knife type where the knife is mounted on a swinging arm, the member is adapted to slide along a stationary guide in unison with the movements of the swinging arm throughout part of the slicing and return strokes thereof, the arrangement being such that relative movement between the swinging arm and

said member results in actuation of the feed mechanism. The movable member may be associated with a locking member for holding it against movement at the commencement of the strokes in order to actuate the feed mechanism. A part movable with the substance-carrier, or the knife-carrier, may be adjustable so as to regulate the thickness of the slices to be cut.

Two embodiments of the invention are illustrated by way of example in the accompanying drawings in which—

Fig. 1 is an elevation, partly in section, of a slicing machine of the reciprocatory carriage type having the invention applied thereto;

Fig. 2 is a fragmentary plan thereof;

Fig. 3 is a fragmentary detail view showing a locking member and associated parts, herein-after referred to;

Fig. 4 is a section on the line IV—IV of Fig. 2; and

Figs. 5 and 6 are elevations of a slicing machine of the swinging arm type having the invention applied thereto, the working parts being shown in different positions.

Referring to Figs. 1 to 4, the slicing machine therein shown comprises a rotary slicing knife 1 which may be driven either by a motor or by hand independently of the reciprocatory carriage 2, the latter being slidably mounted on guide bars 3, 4 mounted on the base plate 5 of the machine. The carriage 2 is adapted to be hand-reciprocated by means of a handle 6 in order to carry the substance 7 to be sliced to and fro past the knife 1. A clamping device 8 is provided for securing the substance 7 to a feed plate 9 adapted to be moved across the carriage 2 toward the knife by an intermittently rotatable feed screw 10 co-acting with a segmental feed nut 11 mounted on one side of the feed plate 9. The feed screw 10 is journaled in a bearing 40 on the carriage 2 and has secured to it a ratchet wheel 12 with which co-acts a pawl 13 at one end of a lever arm 14 pivotally mounted midway of its length on an unthreaded part of the feed screw 10.

It will be apparent that by rocking the arm 14 recurrently, the plate 9 and substance 7 thereon will be fed step-by-step toward the slicing knife, the extent of the feeding movements determining the thickness of the slices severed. It will also be apparent that, by varying the amplitude of the rocking movements, the thickness of the slices will be proportionately varied.

The construction and operation so far de-

scribed are well known in the art and form no part of the present invention.

As shown, the arm 14, at the end thereof opposite the pawl 13, is pin-jointed to one end of a link 15, the other end of which is pin-jointed to a block 16 slidably mounted on the guide bar 3, the latter being of rectangular cross-section. Loosely hinged in a recess 17 formed in a projection 18 at the end of the block 16 remote 10 from the arm 14, is a locking member constituted by a collar 19 which loosely embraces the bar 3. The upper and lower walls of the opening in the collar 19 through which the bar 3 passes are so shaped as to be capable of biting 15 into the bar and thereby lock the block thereon. The collar 19 is normally urged toward its biting position by a spring 20 interposed between it and the block 16. A projection 21 is formed at the end of the block 16 opposite the projection 18 and co-acts with a facing 22 formed in one end of the carriage 2. Adjustably mounted near the other end of the carriage is a rod, 20 strike or abutment member 23 in alignment with the top of the collar 19. The rod 23 is slidably mounted in webs 24 on the underside of the carriage 2 and is movable endwise into one or other of a number of positions by means of a hand lever 25 which co-operates with a notched gate 26 and can be locked in any selected position 25 on the gate 26 by causing a spring-urged 30 detent 27 to engage the proper notch 28. The lever 25 is fulcrumed at 29 on the underside of the carriage 2 and is pivotally connected at 29' to the rod 23.

In operation, the handle 6 is grasped and the carriage 2 is moved toward the knife (i. e. toward the right of Fig. 1, which represents the parts shortly after the movement has commenced). The collar 19 is biting the bar 3 and the block 40 16 is therefore held stationary, so that the facing 22 moves away from the projection 21 and the rod 23 moves toward the collar 19. At the same time, the arm 14 is rocked by the pull of the link 15, so that the feed screw 10 is partially rotated and the substance 7 is advanced 45 across the cutting plane of the knife. The rocking of the arm 14 continues until the collar 19 is released from the bar 3, this being effected when the rod 23 strikes the collar and rocks it 50 against the action of the spring 20, whereafter the block 16 is permitted to slide along the bar 3 in unison with the carriage 2.

When the slicing operation has been carried out, the carriage 2 is returned toward the left by Fig. 1. The rod 23 then moves away from the collar 19 which thereupon moves into its biting position under the action of the spring 20 and locks the block 16 to the bar 3. The arm 14 now returns 55 toward its initial position, which it reaches just as the facing 22 contacts with the projection 21 and urges the block 16 to release the collar 19, whereafter the block 16 moves in unison with the reciprocating carriage 2 throughout the remainder of the return stroke.

If desired, the collar 19 may be provided with a tail-piece 30 and the carriage 2 with a striker 31 adapted to assist in releasing the collar 19, after 60 the commencement of the return stroke of the carriage, by striking the tail-piece 30 and rocking the collar 19; but parts 30 and 31 are unnecessary 70 to the operation of the device shown in Fig. 1, as will be obvious from the previous description.

In the construction shown, adjustment of the position of the rod 23 would result in adjustment 75 of the lost motion between the block 16 and the

carriage 2, this lost motion being proportionate to the amplitude of the rocking movements of the arm 14 and, consequently, of the thickness of the slices to be cut. If desired, however, the rod 23 could be substituted by a fixed abutment on the carriage so that the rocking of the arm 14 would have a constant amplitude. With this arrangement an adjustable shroud of well-known construction and operation could be incorporated in the pawl and ratchet mechanism, whereby the thickness of the slices could be regulated.

It will therefore be obvious that, in the operation of the machine, the operator has simply to set the feed mechanism to give the desired thickness of the slices; thereafter he pushes the carriage until a slice is completely severed and then immediately returns the carriage to a point in which the substance is a short distance beyond the cutting edge of the knife. The slicing operations are thereafter continued until a sufficient 95 number of slices have been cut. The feeding movements are transmitted to the substance automatically at the beginning of each slicing stroke and are quite independent of the extent thereof, no initial adjustment being necessary to suit the 100 width of the substance to be sliced.

In the embodiment of the invention shown in Figs. 5 and 6, the construction and operation is analogous to that already described with reference to Figs. 1 to 4. The invention is shown applied to a slicing machine of the swinging arm type, in which the knife reciprocates relative to the work support, comprising a slicing knife 41 which may be rotated in well-known manner either by swinging the arm 42 to and fro past the substance 110 clamped on the feed plate 49 or independently of the swinging arm by an electric motor. As in the previously described construction, the feed mechanism includes a feed screw 50, a ratchet wheel 52 thereon, a pawl 53, and a lever 54, 54' of which the arm 54 carries the pawl 53. The feed mechanism is adapted to be actuated by a block 56 slidably mounted on a stationary bar 43 secured to the frame 45 of the machine, the block 56 having loosely hinged to it a collar 59 adapted to bite into 120 the bar 43 in order to lock the block 56 temporarily thereto. The collar 59 is continuously urged toward its biting position by a spring indicated at 60. The collar 59 is disposed in the path of a set screw or striker 63, screw-threaded through 125 a bracket 63' on an arm 42' secured to the pivot of the swinging arm 42, and is formed with a tail-piece 70 disposed in the path of a striker 71 on the swinging arm. The arm 42' is disposed at the side of the frame 45 opposite to the swinging arm 42.

In this embodiment, the lever 54 is connected to the block 56 through the intermediary of an articulated system of links and levers comprising a bell crank lever 55 fulcrumed on the arm 42', 135 a link 72 interconnecting one arm of the bell crank lever 55 and the block 56, and two pin-jointed links 73, 74 interconnecting the other arm of the bell crank lever 55 and the lever arm 54', the pin-joint between the links 73, 74 being carried at one end of an arm 75, pivoted at its other end on the frame 45. The above system is so contrived that the pin-joint 55' between the bell crank lever 55 and the link 73 is co-axial with the axis of swing of the arms 42, 42' throughout that 145 part of the slicing stroke subsequent to the actuation of the feeding mechanism, as hereinafter set forth.

In operation, the set screw 63 is adjusted to bring the pin 55' over the center of oscillation of

arm 42. The arm 42 is first of all swung upwards to the operator's right (i. e. to the left of the drawings) clear of the substance, and is then swung downward in the opposite direction to perform the slicing operation. At the commencement of the downward stroke (as shown in Fig. 5) the striker 71 moves away from the tail-piece 70 and permits the collar 59, under the action of the spring 60, to lock the block 56 to the bar 43, the bell crank lever 55 being caused to rock about its fulcrum and the feed mechanism being thereby actuated. When the set screw 63 strikes the collar 59 and releases the block 56, the latter moves along the bar 43. Since the pin-joint 55', throughout the remainder of the slicing stroke, is located substantially in the axis of swing, the lever 54, 54' will remain at rest and the feed mechanism will not be in any way affected. The feed may be varied by a cam on the feed screw 52 to raise the pawl 53 during a predetermined portion of the stroke of member 54'. Such a cam is well known in the art to which this invention pertains.

On the return, or upward, stroke of the swinging arm 42 from its lowermost position (Fig. 6), the set screw 63 will move away from the collar 59 and so permit the block 56 to be locked, resulting in the bell crank lever 55 rocking toward its Fig. 5 position and returning the pawl 53 toward its initial position in readiness for the next feeding stroke. Just as the pawl 53 is about to reach its initial position, the striker 71 contacts with the tail-piece 70 and thereby releases the collar 59, so that the block 56 is caused to slide along the bar 43 and the rocking of the bell crank lever to cease.

As in the previous embodiment, in lieu of arranging to regulate the thickness of the slices by the means shown, a fixed abutment might be provided in place of the set screw 63, and an adjustable shroud incorporated in the pawl and ratchet mechanism for regulating the effective stroke of the pawl.

If desired, the bar 43 could be formed arcuate with the axis of swing of the arm 42 as center.

The embodiments of the invention herein described and illustrated have been chosen simply by way of example and many modifications could be made without departing from the scope of the invention.

I claim:—

1. In a slicing machine having a movable element and a feeding mechanism; a feed actuating mechanism comprising in combination; a guide having a member guided thereby, a latch normally holding said member fixed with relation to said guide, means operatively connecting said member with said feeding mechanism; an abutment mounted on said movable element to release said latch when said movable element is moving in one direction and means on said movable element to move said guided member when said movable element is moved in the opposite direction.

2. In a slicing machine having a movable element and a feeding mechanism; a feed actuating mechanism comprising in combination; a guide having a member guided thereby, a latch normally holding said member fixed with relation to said guide, means operatively connecting said member with said feeding mechanism; an abutment mounted on said movable element to release said latch when said movable element is moving in one direction and means on said movable element to move said guided member when said movable element is moved in the opposite direction.

tion, said abutment comprising a member adjustable to vary the distance between said abutment and said latch.

3. In a slicing machine; a base member; two elements, one movable and the other stationarily mounted on said base member, said elements comprising a slicing knife and a work support; a work feeding mechanism; a guide member mounted on said base, a guided member mounted to move along said guide; means to normally hold said guided member in fixed position on said guide; means connecting said feeding mechanism with said guided member and with said movable element to actuate said feeding mechanism when said movable element is moving and said guided element is held relatively stationary with respect thereto; means carried by said movable element to release said holding means after said movable element has moved through a part of its range of movement and to move said guided member with said movable member to prevent further actuation of said feeding means during movement of said movable element through a further portion of its range of movement.

4. In a slicing machine; a base member; two elements, one of said elements being stationarily mounted on said machine and the other of said elements being mounted for reciprocation relative to the stationary element, one of said elements comprising a slicing knife and the other of said elements comprising a work support; a work feeding mechanism; a guide member on said base, a guided member mounted to move along said guide, means to normally hold said guided member fixed on said guide; means connecting said feeding mechanism with said guided member and with said reciprocative element to actuate said feeding mechanism when said movable element is moving and said guided element is held relatively stationary with respect thereto; means carried by said reciprocating element to release said holding means after said reciprocating element has moved through a part of its range of movement and to move said guided member with said reciprocating element to prevent further actuation of said feeding means during movement of said reciprocating element through a further portion of its range of movement.

5. In combination with a slicing machine having two elements one stationarily mounted and the other mounted for reciprocation relative thereto, said elements comprising a work support and a slicing knife structure; a guide member, a member slidably mounted thereon, means to normally hold said member stationary with respect to said guide member; a feeding mechanism for said work support, means connecting said slidable member, reciprocating element and feeding mechanism to cause the actuation of said feeding mechanism when said reciprocating element is moved in one direction with said slidable member held stationary, said connecting means being inoperative to actuate said feeding mechanism but causing a resetting thereof when said reciprocating element is moved in the opposite direction with said slidable member held stationary.

6. In combination with a slicing machine having two elements one stationarily mounted and the other mounted for reciprocation relative thereto, said elements comprising a work support and a slicing knife structure; a guide member, a member slidably mounted thereon, means to normally hold said member fixed on said bar, a feeding mechanism for said work support, means con-

necting said slidable member, reciprocating element, and feeding mechanism to cause the actuation of said feeding mechanism when said reciprocating element is moved in one direction with said slidable member held stationary, said connecting means being inoperative to actuate said feeding mechanism but causing a re-setting thereof when said reciprocating element is moved in the opposite direction with said slidable member held stationary; means on said reciprocating element to engage and release said holding means when said reciprocating element is moved in said first-mentioned direction and to move said slid- 10 able member with said reciprocating element thereby rendering said feeding mechanism inoperative, and means on said reciprocating element effective during its reverse movement, and after said first-mentioned means on said element has disengaged said holding means, to return said slidable member to its position occupied before its engagement with its first-mentioned means on said element.

7. In combination with a slicing machine having two elements one stationarily mounted and the other mounted for reciprocation relative thereto, said elements comprising a work support and a slicing knife structure; a work feeding mechanism including a feed screw connected to actuate one of said elements and having a ratchet thereon, a pivotally mounted lever having a pawl at one end to engage said ratchet; a guide member having a member slidably mounted thereon; means to normally hold said slidable member fixed on said guide; means connecting said slid- 25 able member, reciprocating element and lever to impart rotation to said screw through said pawl and ratchet when said reciprocating element is moved in one direction with said slidable member held stationary, said connecting means causing a re-setting of said pawl on said ratchet when said reciprocating element is moved in the opposite direction with said slidable member held stationary.

8. The combination set forth in claim 7 wherein said abutment member is adjustable relative to said latch bar to vary the rotative movement imparted to said feed screw.

9. In a feeding mechanism for slicing machines having a stationary element and a reciprocating element; a feed screw connected to actuate one of said elements and having a ratchet thereon, a pivoted lever carrying a pawl to engage said ratchet; a guide having a member slidably mounted thereon, a latch normally holding said member fixed on said guide; means connecting said member, reciprocating element and lever to impart rotative movement to said lever when said element is reciprocated while said member is held stationary.

10. In a feeding mechanism for slicing machines having a stationary element and a reciprocating element; a feed screw connected to actuate one of said elements and having a ratchet thereon, a pivoted lever carrying a pawl to engage said ratchet; a guide having a member slidably mounted thereon, a latch normally holding said member fixed on said guide; means connecting said member, reciprocating element and lever to impart rotative movement to said lever when said element is reciprocated while said member is held stationary, said reciprocating element carrying an abutment member to release said latch and move it with said element after said element has started to move in one direction; said reciprocating element having means to engage and move said member therewith when said

element moves in the opposite direction; the position of said member being so related to said abutment and said last-mentioned means that said last-mentioned means engages said member after said abutment has moved away from said latch.

11. In a slicing machine having a slicing knife and a reciprocating work support; a feeding mechanism for said work support; a guide having a member slidably mounted thereon; latch means releasably holding said member to said guide; means connecting said member, support, and feeding mechanism to actuate said feeding mechanism when said support is moving and said member is held relatively stationary.

12. In a slicing machine having a slicing knife and a reciprocating work support; a feeding mechanism for said work support; a guide having a member slidably mounted thereon; said work support, feeding mechanism and member being connected together to actuate said feeding mechanism when said support is moving in one direction with said member held stationary and to re-set said feeding mechanism to initial operative position when said support is moving in the opposite direction with said member held stationary, and means co-operating between said member and work support to reciprocate said member on said guide during a portion of each reciprocative movement of said work support.

13. In a slicing machine having a slicing knife and a work support mounted for reciprocation past the edge of said knife; a ratchet operated feed screw on said work support and connected therewith to move it toward and away from said knife upon rotation of said screw; a lever pivoted on said screw and having a pawl at one end to engage said ratchet, a guide having a member slidably mounted thereon, a latch normally holding said member fixed on said guide, a lever pivoted to said member and to the other end of said first-mentioned lever; an abutment mounted on said work support at one side of said latch to contact therewith and release said latch during movement of said support in one direction and means on said support to contact with said member and move said member with said support when said support moves in the opposite direction.

14. In a slicing machine having a slicing knife and a work support mounted for reciprocation past the edge of said knife; a ratchet operated feed screw on said work support and connected therewith to move it toward and away from said knife upon rotation of said screw; a lever pivoted on said screw and having a pawl at one end to engage said ratchet, a guide having a member slidably mounted thereon, a latch normally holding said member fixed on said guide, a lever pivoted to said member and to the other end of said first-mentioned lever; an abutment member mounted on said work support at one side of said latch to contact therewith and release said latch during movement of said support in one direction and means on said support to contact with said member and move said member with said support when said support moves in the opposite direction, said abutment comprising a slidably mounted rod, and means to adjust said rod to vary the distance between the end of said rod and said latch.

15. In a slicing machine having a slicing knife and a reciprocating work support, a feed mechanism connected with said work support to move it toward and away from the plane of the edge of said knife; a guide upon which said work support is mounted; a member slidably mounted on

20. In a slicing machine, the combination with a slicing knife and a work support mounted for relative reciprocating movement, manual means for moving said slicing knife and work support relative to each other over any selected portion of their permitted path of relative movement, feeding mechanism for moving said work support toward the cutting plane of said knife, a member operatively connected to said feeding mechanism adapted to actuate said feeding mechanism during the relative movement of said knife and support toward each other and automatically operable at the beginning of the movement of said knife and support toward each other irrespective of the relative positions of said knife and said support when the knife and support begin their movement toward each other, and means for engaging said member during said relative reciprocation for rendering said member inoperative to actuate said feeding mechanism, said member being engaged only after a selected predetermined amount of said first mentioned relative movement of said knife and said support toward each other. 80
16. In a slicing machine the combination with a slicing knife, of a work support, said knife and work support being mounted for relative movement to cut slices from material on said support, feeding means for feeding said material towards the cutting plane of said knife, a member for actuating said feeding means, means for normally holding said member in a stationary position, said feeding means being operated by said member and while said member is in its normal position, and means operable during the movement of said knife and support relatively to each other for moving said member out of its normal position to thereby interrupt the feeding movement being given to said support. 85
17. In a slicing machine, the combination with a slicing knife and a work support mounted for relative reciprocating movement substantially parallel to the cutting edge of the knife, of a feeding mechanism for moving said work support towards the cutting plane of said knife to thereby position the material in a position such that slices may be cut therefrom by said slicing knife as said knife and support move relative to each other, a member operatively connected to said feeding mechanism adapted to actuate said feeding mechanism during the relative movement of said knife and said support toward each other during said first mentioned relative movement, means for engaging said member during said first relative reciprocation for rendering said member inoperative to actuate said feeding mechanism, said member being engaged only after a selected predetermined feeding movement has been given to said support, and means for varying the distance through which said engaging means moves before it engages said member to render said member inoperative. 90
18. A slicing machine comprising a movable table, a member normally stationary during movement of said table, feeding mechanism on said table for feeding material along said table and operatively connected to said member, said member causing actuation of said feeding mechanism while said member is stationary and means for rendering said member inoperative to actuate said feeding means comprising means constructed to move said normally stationary member and thereby prevent said member from actuating said feeding mechanism. 95
19. In a slicing machine, the combination with a slicing knife, of a work support, said knife and work support being mounted for relative movement to cut slices from material on said support, feeding means for feeding said material towards the cutting plane of said knife, a member for actuating said feeding means, means for normally holding said member in a stationary position, said feeding means being operated by said member and while said member is in its normal position, and means operable during the movement of said knife and support relatively to each other for moving said member out of its normal position to thereby interrupt the feeding movement being given to said support, said last mentioned means being adjustable to vary the time of interruption of said feeding movement. 100
20. In a slicing machine, the combination with a stationary support, an arm pivoted on said support, a knife rotatably carried by said arm eccentric to the pivot of said knife, a second support for the substance to be sliced, means for feeding said second support toward the cutting plane of said knife, said feeding mechanism being actuated by the movement of said arm through connecting mechanism comprising a bell crank having two arms pivoted intermediate its arms, a third support movable in unison with said first arm and controlled thereby and pivoted concentric with the pivot for said first arm, means connecting one arm of said bell crank to said feeding mechanism, a releasable clutch mechanism connected to the other arm of said bell crank, 105 said clutch mechanism being normally held stationary with respect to said second support by means comprising said clutch mechanism to cause feeding movement to be imparted to said feeding mechanism through said interconnecting means, and means controlled by the movement of said first arm for releasing said clutch mechanism after a predetermined movement of said first arm to prevent further feeding movement of said substance support. 110
21. In a slicing machine, the combination with a stationary support, an arm pivoted on said support, a knife rotatably carried by said arm eccentric to the pivot of said knife, a second support for the substance to be sliced, means for feeding said second support toward the cutting plane of said knife, said feeding mechanism being actuated by the movement of said arm through connecting mechanism comprising a bell crank having two arms pivoted intermediate its arms, a third support movable in unison with said first arm and controlled thereby and pivoted concentric with the pivot for said first arm, means connecting one arm of said bell crank to said feeding mechanism, a releasable clutch mechanism connected to the other arm of said bell crank, 115 said clutch mechanism being normally held stationary with respect to said second support by means comprising said clutch mechanism to cause feeding movement to be imparted to said feeding mechanism through said interconnecting means, and means controlled by the movement of said first arm for releasing said clutch mechanism after a predetermined movement of said first arm to prevent further feeding movement of said substance support. 120
22. A device as claimed in claim 21 in which the releasable clutch mechanism has means associated therewith for engaging means on said first arm to return said releasable clutch mechanism to its normal position on the stroke of said knife opposite to that stroke which causes feeding movement so that the clutch mechanism is again operatively positioned to effect the next feeding movement of the substance support. 125
23. A device as claimed in claim 21 in which an adjustable stop is used to release said clutch mechanism at different positions of said first arm in its path of movement. 130
24. In a slicing machine having a work support and a slicing knife mounted to reciprocate past said work support, a feeding mechanism for said work support, a guide having a member slidably mounted thereon, latch means releasably holding said member to said guide, a pivotally mounted arm upon which said knife is mounted, means connecting said member, arm and feeding mechanism constructed to move, and in moving actuate said feeding mechanism when said arm is moving and said member is held relatively stationary. 140
25. In a slicing machine having a work support 135

- and a pivoted arm carrying a slicing knife, said arm being mounted to swing said knife to and fro past said work support, a feeding mechanism for said work support, a guide having a member slidably mounted thereon, latch means releasably holding said member to said guide, means connecting said member, arm and feeding mechanism constructed to move, and in moving actuate said feeding mechanism when said arm is moving in one direction and while said member is held by said latch means and means to re-set said feeding mechanism to initial operative position when said arm is moving in the opposite direction with said member held stationary, and means co-operating between said member and arm to reciprocate said member on said guide during a portion of each to and fro movement of said arm.
26. In a slicing machine having a work support and a slicing knife mounted to reciprocate past said work support, a feeding mechanism for said work support, a guide having a member slidably mounted thereon, latch means releasably holding said member to said guide, a pivotally mounted arm upon which said knife is mounted, means connecting said member, arm, and feeding mechanism constructed to move, and in moving actuate said feeding mechanism while said arm is moving in one direction and said member is held relatively stationary, abutment members mounted on said arm one of which is adapted to release said latch when said arm is moving in said first direction and the other of which is adapted to move said member on said guide when said arm is moving in the opposite direction.
27. In a slicing machine having a work support and a slicing knife mounted to reciprocate past said work support, a feeding mechanism for said work support, a guide having a member slidably mounted thereon, latch means releasably holding said member to said guide, a pivotally mounted arm upon which said knife is mounted, means connecting said member, arm, feeding mechanism constructed to move, and in moving actuate said feeding mechanism while said arm is moving and said member is held relatively stationary, said means comprising a pivoted bell crank lever mounted to move with said arm, a lever connecting said member with one arm of said bell crank lever and a lever pivoted to the other end of said bell crank lever and connected with said feeding mechanism, and means moving with said arm to release said latch as said arm moves in one direction.
28. In a slicing machine having a work support and a slicing knife mounted to reciprocate past said work support, a feeding mechanism for said work support, a guide having a member slidably mounted thereon, latch means releasably holding said member to said guide, a pivotally mounted arm upon which said knife is mounted, means connecting said member, arm, feeding mechanism constructed to move, and in moving actuate said feeding mechanism while said arm is moving and said member is held relatively stationary, said means comprising linkage mounted to move with said arm and connected with said member and a link pivotally connected at one end to said linkage and pivotally connected at its other end to said feeding mechanism, said last mentioned pivotal connection being arranged to extend co-axially with the pivot of said arm in certain positions of said arm with respect to said member and while in said positions, rendering said feeding mechanism inoperative.
29. In a slicing machine having a work support and a slicing knife mounted to reciprocate past said work support, a feeding mechanism for said work support, a guide having a member slidably mounted thereon, latch means releasably holding said member to said guide, a pivotally mounted arm upon which said knife is mounted, means connecting said member, arm, and feeding mechanism to actuate said feeding mechanism when said arm is moving and said member is held relatively stationary, abutment members mounted on said arm one of which is adapted to release said latch when said arm is moving in one direction and the other of which is adapted to move said member on said guide when said arm is moving in the opposite direction, said connecting means comprising linkage mounted to move with said arm and connected with said member and a link pivotally connected at one end to said linkage and connected at its other end to said feeding mechanism, said pivot being arranged to extend co-axially with the pivot of said arm when said member is moved by said abutment members on said arm.
30. In a slicing machine having a work support and a pivoted arm carrying a slicing knife eccentric of the pivot of said arm, said arm being mounted to swing said knife to and fro past said work support, a guide bar having a member slidably mounted thereon; a feeding mechanism comprising a feeding screw, a ratchet to rotate said screw, a bell crank pivotally mounted on said screw, a pawl mounted on one arm of said bell crank to engage said ratchet, linkage mounted to move with said first mentioned arm and connected with said member, said linkage being pivoted to a lever forming a connecting means to said other bell crank arm, said first mentioned arm having abutments to reciprocate said member on said guide during a part of each movement of said arm and said member having means to hold it stationary on said guide during the remainder of each movement of said arm.
31. In a slicing machine having a work support and a pivoted arm carrying a slicing knife eccentric of the pivot of said arm, said arm being mounted to swing said knife to and fro past said work support, a guide bar having a member slidably mounted thereon, a feeding mechanism comprising a feeding screw, a ratchet to rotate said screw, a bell crank pivotally mounted on said screw, a pawl mounted on one arm of said bell crank to engage said ratchet, linkage mounted to move with said first mentioned arm and connected with said member, said linkage being pivoted to a lever forming a connecting means to said other bell crank arm, said first mentioned arm having abutments to reciprocate said member on said guide during a part of each movement of said arm, said member having means to hold it stationary on said guide during the remainder of each movement of said arm and said linkage and lever being proportioned to position the pivot of said lever co-axial to the pivot of said arm while said member is being moved by said arm.
32. In a slicing machine having a work support and a pivoted arm carrying a slicing knife eccentric of the pivot of said arm, said arm being mounted to swing said knife to and fro past said work support, a guide having a member slidably mounted on said guide, a feeding mechanism, a bell crank lever mounted to swing with said arm and pivoted eccentrically of the pivot of said arm.

arm, a link connecting one arm of said bell crank with said member and a link pivotally connected to the other arm of said bell crank and to said feeding mechanism, and means co-operating between said member and arm to reciprocate said member on said guide during a portion of each to and fro movement of said arm.

33. The combination set forth in claim 32 wherein said bell crank lever and links are proportioned to position the pivotal connection between said second-mentioned link and said second mentioned arm of said bell crank co-axial with the pivot of said first mentioned arm when said member is reciprocated by said co-operating means.

34. In a slicing machine, the combination with a slicing knife, of a support for said knife, a work support mounted for manually controlled reciprocating movement relatively to said support, said work support and knife support being free to move over any portion of a predetermined path of relative travel to effect different amounts of relative movement between said knife and work support when manually moved, a work feeding mech-

anism on said work support positively operated by actuating mechanism connected to said knife support and work support and operable by said knife support and work support through said mechanism as the latter two elements move relative to each other in opposite directions, said actuating mechanism including means automatically operable to initiate and stop the movement of the feeding mechanism at spaced points in the path of relative travel of said supports, the distance between said points being always the same for successive relative movements for a given amount of feeding movement of said feeding mechanism and irrespective of the point in said path at which said relative movement is begun, and said actuating mechanism also including means for effecting complete feeding of said feeding mechanism while said relative movement between said points takes place regardless of the point in said path where the relative movement is begun so long as said supports move relative to each other a total distance equal to the distance between said first two mentioned points.
